UNITED STATES PATENT OFFICE.

WILLIAM J. H. STRONG, OF CHICAGO, ILLINOIS.

HEAT MOTOR.

1,420,672.

Specification of Letters Patent. Patented June 27, 1922.

Application filed May 6, 1916. Serial No. 232,820.

To all whom it may concern:

Be it known that I, WILLIAM J. H. STRONG, a citizen of the United States, and a resident of Chicago, county of Cook, and 5 State of Illinois, have invented a certain new, useful, and Improved Heat Motor, of which the following is a full, clear, concise, and exact description, reference being had to accompanying drawings, forming a part 10 of this specification.

My invention relates to improvements in heat motors and has special reference to improvements in a portable combined hot air motor and fan.

15 Among the several objects of my invention are to provide a light strong open-work motor supporting structure or base which can readily be secured to the body of the motor and as easily separated therefrom for 20 shipping purposes, which base shall comprise three independent flat leg members adapted to be separately secured to the motor and when removed from the motor adapted to be packed within a minimum 25 space for shipment.

A further object of my invention is to provide a hot air motor with very simple means for removably holding and supporting a font for liquid fuel, in place, and from 30 which the font can be easily and quickly released.

My invention resides in a hot air motor adapted to use a liquid fuel, having a vertical working cylinder, a light open work or 35 skeleton base, attached at its upper end to the cylinder and supporting the cylinder at a suitable height, the base provided with yielding arms adapted to engage and hold a fuel font below the cylinder, the arms being 40 capable of being drawn outward against their resiliency to release the font.

My invention also consists in a hot air motor of the class described, and having a light, skeleton base, comprising three vertically arranged leg members made of strap metal, and each leg carrying a depending yielding arm formed for engagement with the periphery of a fuel font, and at least one 45 of the arms provided with a hooked finger piece whereby the arm may be readily withdrawn to permit the removal or placement 50 of the fuel font.

My invention also consists in the several arrangements and combinations of parts 55 and in the features of construction, whereby I am enabled to attain the above described,

and other objects, and all as hereinafter described, and particularly pointed out in the appended claims.

My invention will be more readily understood by reference to the accompanying drawings forming a part of this specification and in which:

Figure 1 is a fragmentary side elevation of a combined hot air motor and fan illustrating one embodiment of my invention;

Figure 2 is a horizontal plan view of the base taken on the line 2—2 of Figure 1; and

Figure 3 is a vertical sectional view of the lower part of the motor and the base taken 70 on the line 3—3 of Figure 2.

A special object of my invention is to provide a low base especially adapted for use with the hot air motor and fan disclosed in my copending application for 75 Letters Patent of the United States entitled Hot air motor, Serial No. 170,115, filed May 21st, 1917.

The form of motor and base disclosed in 80 said application is particularly arranged for use with a kerosene lamp as the source of heat, as well as other forms of fuel, and for said special purpose requires a considerable space below the motor for the reception of the lamp.

85 The present invention relates more particularly to the use of alcohol or gasoline as a fuel, which permits the use of a low base, of very simple construction.

In the drawings 1 denotes generally a hot 90 air motor, such as disclosed in my said copending application, provided with a working cylinder 2, a generator cylinder 3 depending therefrom, a shaft housing 4 above the cylinder and a spacing member or cylinder 4' supporting the shaft housing upon the cylinder 2. While the motor may be used for different power purposes, I have 95 illustrated the motor as provided with a ventilating fan 5, mounted upon the shaft of the motor.

The generator cylinder 3 is secured at its upper end to the lower end of the working cylinder and depends therefrom. Below the lower end 6 of the generating or hot air 105 cylinder I provide a fuel font 7 which is low and of relatively large diameter, and is provided with a centrally arranged burner 8 adapted to impinge its flame upon the lower end 6 of the generating cylinder.

110 For supporting the font 7 close to the floor, and the motor at the proper height

above the font, I provide three similar legs 9, equi-spaced around the motor and each comprising a unitary structure independently secured to the cylinder 2 and each 5 adapted to assist in providing a relatively low base. These legs are made of strap or strip metal and each consists of a main leg member 9 consisting of a vertical part 10 and an outwardly inclined section 11 10 terminating in a curved foot part 12. The securing or attaching section 10 is bent inwardly at its upper end providing an attaching lug 13 provided with a flat upper surface adapted to contact with the lower 15 surface of an annular supporting flange 14 provided on the cylinder 2 adjacent to its lower end. Each member 9 is securely attached to the motor at its upper end by a screw 15, a hole being provided in the flange 20 15 therefor.

Surrounding the lower end of the generator cylinder 3 is a guard cylinder 16 which depends below the lower end of the cylinder 3 and has a contracted lower end with a central opening 17 for the insertion of the burner 8. This guard cylinder 16 is of a diameter to be received between the several vertical portions 10 of the several legs and each leg is secured to the cylinder by a screw 18. The cylinder 16 thus serves the double purpose of its function relating to the motor of a guard cylinder and the added function of forming a part of the base to assist in holding the three leg members 30 rigidly together. The outwardly inclined lower end 11 of the leg members 9 provide a central space between the legs for the reception of the fuel font 7.

To brace the leg members 9 I provide a brace member 18 for each leg, having its upper end 19 riveted or otherwise securely fastened to the vertical part 10 of the leg member 9 adjacent to its upper end, and having its lower end 20 secured by a rivet 40 or otherwise to the outwardly inclined part 11 of the main leg member 9. The brace member 18 thus serves to make the leg a rigid base supporting member and the three legs in combination with the guard cylinder 45 16 form a rigid base adapted to support the motor in a stable condition.

To support the font 7 in proper central position in the space between the several legs and centrally beneath the generator cylinder 3, I provide on each leg a depending font engaging arm or member 21 secured at its upper end to the main leg member adjacent to the upper end of the inclined portion 11, and provided at its lower end with 55 an inwardly formed shoulder 22 adapted to project beneath the edge of the font 7 and support the same. The arm 21 is a spring arm and I form it to normally stand in the inner dotted position when the font is not 60 65 in place.

The font is of peculiar contour at its periphery, having a relatively deep conical upper part 23 and a sharper lower conical outer edge 24. The upper part 23 of the periphery is adapted to spread the spring 70 supporting members when the motor is lifted and placed down upon the font, the font thus entering between the several supporting members 21 and spreading them apart until the shoulders 22 pass the larger periphery 75 23 of the font. When this point is reached the resiliency of the several arms causes them to enter beneath the font and automatically raise it to its proper position as shown in full lines. To release the font 80 from its supported position, one or more of the arms 21 are drawn or forced outwardly to permit the font to pass the shoulder 22, and for conveniently forcing the arms out for this purpose, each of which is provided 85 with a finger hook piece 26 at its lower end in convenient position to be grasped by the hand when grasping the leg and be pulled outwardly to the dotted position. When one or more of the supports 21 are thus 90 drawn out, the font can be freely removed from its operative position, or a font can be readily entered into operative position.

As shown and described, the leg members 8 are independent of each other and are 95 each independently secured to the motor by means of the flange 14 and screws 15 and are rigidly secured together by means of the guard 16 and screws 18. They are relatively thin or flat and when removed from the motor can be stacked or arranged compactly together to occupy a minimum space for shipment. The importance of this feature will be recognized when it is understood that most of the motors of this form manufactured, are shipped to foreign countries, and it is necessary in this trade to reduce the shipping space required for each motor to a minimum.

As many modifications of my invention 110 will readily suggest themselves to one skilled in the art, I do not limit or confine my invention to the specific structures herein shown and described except as defined by the appended claims.

I claim:

1. In a hot air motor, an open work stand for supporting the motor at a proper height and for supporting a fuel font below the motor, said stand comprising a plurality of 120 relatively flat leg members arranged to be removably attached at their upper ends to the body of the motor, a guard cylinder on the lower end of the motor between the legs and to which the legs are removably attached, and a shouldered font holding spring member within each leg and adapted to yieldingly hold a fuel font in place.

2. In a hot air motor, a supporting base therefor comprising a plurality of inde- 130

pendent and separate vertically arranged and equi-spaced leg members, said leg members attached at their upper ends to the body of the motor, the motor having a dependent generator cylinder, a circumferential flange on the generator cylinder and each of said leg members independently secured to said flange.

3. In a hot air motor, a supporting base therefor comprising a plurality of independent and separate vertically arranged and equi-spaced leg members, said members attached at their upper ends to the body of the motor, a motor having a dependent generator cylinder, and a circumferential flange surrounding the generator cylinder, each of said leg members being independently secured to said flange, and each leg provided with a shouldered font engaging member 20 for holding a fuel font below said generator cylinder.

4. In a hot air motor, a skeleton base, a fuel font arranged within said base, yielding arms rigidly secured at their upper ends to the base and formed at their free lower ends for engagement with the periphery of the fuel font, a hooked finger piece on each said arm for convenience in withdrawing the arms for releasing the font, 30 each arm arranged within and guarded by a leg member.

5. In a hot air motor, a skeleton base, the motor having a generator cylinder dependent within the base, a fuel font arranged

below the generator cylinder, depending 35 spring arms carried by the base, their lower free ends adapted for engagement with the periphery of the fuel font to support same, hooks on said arms for manipulating the arms to release the font, the base having vertical leg members one arranged outside of 40 and guarding each of said arms.

6. In a hot air motor, a skeleton base composed of at least three vertically arranged independent leg members, a depending font 45 supporting arm arranged within and secured on each leg, the free end of each said arm normally pressed inwardly for engagement with a font, and at least one of said arms being bent at its free end into a 50 hooked finger piece for withdrawing same.

7. In a hot air motor, a skeleton base composed of at least three vertically arranged leg members, each independently attached at its upper end to the motor proper, a 55 yielding arm carried within each leg member, each arm rigidly attached at one end to its respective leg member and its free end extending inwardly, the free ends of the arms bent to form hooks for convenience 60 in withdrawing the supports, and each bent to form a notch between its ends for engagement with the periphery of a fuel font.

In witness whereof, I hereunto subscribe 65 my name this 26th day of April, A. D. 1918.

WILLIAM J. H. STRONG.
